US0D1102856S

(12) **United States Design Patent** (10) **Patent No.:** **US D1,102,856 S**
(45) **Date of Patent:** **** Nov. 25, 2025**

(54) **RATCHET TENSIONER**

(71) Applicant: **Jiangsu Duolite Crane Machinery Manufacturing Co., Ltd.**, Xuzhou (CN)

(72) Inventor: **Jin Ma**, Xuzhou (CN)

(**) Term: **15 Years**

(21) Appl. No.: **29/947,473**

(22) Filed: **Jun. 14, 2024**

(51) LOC (15) Cl. **08-05**

(52) U.S. Cl. **D8/44**

(58) **Field of Classification Search**

USPC D8/14, 44, 51, 367, 356

CPC F16G 11/12; F16G 11/10; B25B 25/00

(57) **CLAIM**

The ornamental design for a ratchet tensioner, as shown and described.

DESCRIPTION

FIG. 1 is a top, front, and right side perspective view of a ratchet tensioner, showing my new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of a portion labelled 9 in FIG. 1. The dash dot dash lines in FIG. 1 and FIG. 9 are for the purpose of depicting the boundary of the enlarged view and form no part of the claim.

1 Claim, 9 Drawing Sheets
